UNITED STATES PATENT OFFICE

ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

SLEEVE-VALVE ENGINE

Application filed December 5, 1927. Serial No. 237,611.

This invention relates to internal combustion engines and refers more particularly to the sleeve valve type of engine. In this type of engine the upper extremity of the sleeve 5 or sleeves ordinarily works in a pocket formed between the cylinder head and cylinder. While the cylinder head is ordinarily jacketed for cooling water, the amount of available jacketing is limited due to spark 10 plug location and general arrangement of parts. As a result the sleeve jacket tends to become overheated resulting in carbon accumulation and general inefficient operation of the engine.

One of the objects of my invention resides in providing means for overcoming the above objectionable characteristics. To this end I have provided improved means associated with the cylinder head and cylinder 20 head cover for causing a positive circulation of cooling water for cooling the cylinder head, sleeve pocket, and spark plug.

I have provided a member preferably in the nature of a simple sheet metal stamping 25 associated with the cylinder head and cover for guiding the water in the desired circulating path. One feature of my invention resides in a construction which will not require division of the cylinder head jacket by 30 partitions, thus simplifying the casting operations and reducing the manufacturing cost.

Further features and advantages of my invention reside in the simplicity of the parts, 35 lightness of weight, and ability to be manufactured at low cost.

Further features of my invention reside in the novel combination and arrangement of parts more particularly hereinafter described and claimed.

Referring to the accompanying drawings in which like reference characters represent corresponding parts,

Fig. 1 is a sectional elevation view transversely of the engine through a typical engine cylinder along 1—1 of Fig. 5,

Fig. 2 is a sectional view at right angles to Fig. 1 longitudinally of the engine along 50 2—2 of Fig. 5,

Fig. 3 is a perspective view of the cylinder head,

Fig. 4 is a perspective view of the water deflecting member, and

Fig. 5 is a top plan view of a cylinder 55 head and water deflecting member.

In the drawings reference character 10 represents one or more engine cylinders with associated sleeve valve 12, the latter for illustration being shown as the "Burt-McCollum" single sleeve valve type in which the sleeve is moved in a combined reciprocating and oscillating path with respect to the sleeve axis in moving the sleeve ports 13 to function with the cylinder ports 14.

The cylinder is closed at the top by a cylinder head 15 which may be formed with walls 16 and 17. The wall 16 together with the associated cylinder forms a valve pocket 17^a accommodating the movement of the upper portion of the sleeve valve 12. The wall 17 is spaced from the wall 16 to form the cylinder head cooling water jacket 18 and also defines the combustion chamber 19. The wall 17 may be extended to provide a barrel 70 20 with the spark plug opening 21 for spark plug 11. The cylinder head 15 may be secured to the cylinder by studs 22 at the corners of the cylinder head flange 23.

The cooling water from jacket 24 is open 80 for communication with the cylinder head jacket 18 through opening 25 preferably mainly along one side only of the cylinder head as shown in Figs. 1 and 5. For guiding the water from opening 25 I have provided a member 26 preferably formed of a sheet metal stamping. The member 26 may be formed with wall 27 spaced from the side of the cylinder head adjacent the opening 25, side walls 28, and top wall 29. The 85 water in moving across the cylinder head is caused to circulate downwardly into the jacket 18 by reason of the baffles 31 preferably formed integrally with the main body of the member 26. The top wall 29 is 90 formed with a semi-circular or recessed portion 32 engageable with the barrel 20 preferably below the sealing structure or ring 33. A nut 34 threadedly engages barrel 20 for 95 clamping the cylinder head cover 35 and 100

sealing ring 33 in position as shown in the drawings.

The members 26 may be conveniently seated on the tops of the cylinders 10 intermediate the cylinder heads 15 and cover 35. The baffles 31 preferably are located between the plane of the cylinder axes and the side of the engine having the water openings 25. By such an arrangement the water is deflected downwardly into the cylinder head jacket 18 insuring adequate and improved cooling particularly for the spark plug 11 at the opening 21. In some instances I may provide the barrel ring flange 30 with the strengthening webs 38 above and outside of the cylinder head jacket 18, these webs to a slight degree preventing passage of water across and above the cylinder head jacket. The baffles 31 deflect practically all of the water into the jacket and if desired the webs 38 may be dispensed with.

The cooling water may be circulated throughout the entire system by the usual water pump (not shown), the water being returned to the usual radiator by a header 37 on the outlet side of baffles 31.

My invention is obviously equally well adapted for use with various types of sleeve valve engines such as multiple or single sleeves having various movements.

What I claim as my invention is:

1. An internal combustion engine of the sleeve valve type comprising in combination, a plurality of water jacketed cylinders, a water jacketed cylinder head forming a sleeve pocket with each cylinder and provided with a barrel portion, a cylinder head cover through which said barrel extends, a sealing ring between the barrel and cylinder head cover, and a member intermediate the cylinder head cover and cylinder head constructed to form a water deflecting passage in conjunction with the cylinder head jacket and provided with a downwardly extended baffle positioned to one side of the plane of the cylinder axes for directing water from the cylinder jacket to flow generally downwardly into and across the cylinder head.

2. An internal combustion engine of the sleeve valve type comprising in combination, a water jacketed cylinder, a water jacketed cylinder head forming a sleeve pocket with the cylinder and provided with a barrel portion, a cylinder head cover through which said barrel extends, a sealing ring between the barrel and cylinder head cover, and a member intermediate the cylinder head cover and cylinder head having a recessed portion embracing the barrel and being constructed to form a water deflecting passage in conjunction with the cylinder head jacket for directing water from the cylinder jacket to flow generally downwardly into and across the cylinder, said member having a downwardly extending baffle positioned to one

side of a plane longitudinally of the engine and containing the cylinder axis.

3. An internal combustion engine of the sleeve valve type comprising a cylinder, a cylinder head having a water jacket portion depending into said cylinder and an upstanding barrel portion, a cylinder head cover, a member within the cover, said member and barrel having cooperating means above the cylinder head jacket for directing cooling water into the cylinder head jacket.

4. An internal combustion engine of the sleeve valve type comprising a cylinder, a cylinder head having a water jacket portion depending into said cylinder and an upstanding barrel portion, said barrel having a web projecting outwardly therefrom above the cylinder head jacket, a cylinder head cover, a member within the cover, said member having a baffle cooperating with the barrel web for directing cooling water into the cylinder head jacket.

5. An internal combustion engine of the sleeve valve type comprising in combination, a water jacketed cylinder, a water jacketed cylinder head forming a sleeve pocket with the cylinder and provided with a barrel portion, a cylinder head cover through which said barrel extends, a sealing ring between the barrel and cylinder head cover, and a sheet metal member intermediate the cylinder head cover and cylinder head having a recessed portion embracing the barrel and being constructed to form a water deflecting passage in conjunction with the cylinder head jacket for directing water from the cylinder jacket to flow generally downwardly into and across the cylinder head, said barrel having a lateral deflecting projection above the cylinder head jacket cooperating with the said member.

6. An internal combustion engine of the sleeve valve type comprising a cylinder, a cylinder head having a water jacket portion depending into said cylinder and an upstanding barrel portion, said barrel having a sealing ring supporting flange and a web therebelow, a cylinder head cover, a member within the cover cooperating with the cylinder head and barrel web for directing cooling water into the cylinder head jacket, and a sealing ring between the barrel and cylinder head cover supported by said barrel flange.

7. A sleeve valve engine comprising a cylinder, a cylinder head, a cylinder head cover, a member within the cover, said member and cylinder head having cooperating deflectors located above the cylinder head jacket for guiding cooling water into the cylinder head.

8. A sleeve valve engine comprising a cylinder, a cylinder head, a cylinder head cover, a member within the cover, said cylinder head and member having cooperating

deflectors for guiding cooling water into the cylinder head, said deflectors being positioned to one side of the plane longitudinally of the engine through the cylinder axis of said members and engageable with the other preventing displacement of the second member from the water flow.

9. A sleeve valve engine comprising a cylinder, a cylinder head, a cylinder head cover, a member within the cover having a water deflecting baffle positioned to one side of the plane longitudinally of the engine through the cylinder axis for guiding cooling water into the cylinder head.

10. A sleeve valve engine comprising a cylinder, a cylinder head, a cylinder head cover, a member within the cover having a baffle positioned to one side of a plane longitudinally of the engine through the cylinder axis for guiding cooling water into the cylinder head, said member having a recessed portion engageable with the cylinder head.

11. A sleeve valve engine comprising a cylinder, a cylinder head having a water jacket portion depending within the cylinder and an upstanding barrel portion, a cylinder head cover, a member within the cover having spaced baffles positioned to one side of a plane longitudinally of the engine through the cylinder axis, said barrel having spaced projections cooperating with said baffles and located above the cylinder head water jacket.

12. A sleeve valve engine comprising a cylinder, a cylinder head having a water jacket portion depending within the cylinder and an upstanding barrel portion, a cylinder head cover, a member within the cover having spaced baffles positioned to one side of a plane longitudinally of the engine through the cylinder axis, said barrel having spaced projections cooperating with said baffles and located above the cylinder head water jacket, said projections lying in a plane containing the said baffles.

13. A sleeve valve engine comprising a cylinder, a cylinder head having a water jacket portion depending within the cylinder and an upstanding barrel portion, a cylinder head cover, a member within the cover having spaced baffles positioned to one side of a plane longitudinally of the engine through the cylinder axis, said barrel having spaced projections cooperating with said baffles and located above the cylinder head water jacket, said projections lying in a plane containing the said baffles substantially parallel with the first said plane.

14. In a sleeve valve engine, a cylinder head, a cylinder head cover, a member within the cover having a water deflecting baffle, and a second baffle separate from said member but cooperating therewith to deflect water into the cylinder head, said baffles being positioned to one side of the plane longi-

tudinally of the engine through the cylinder axis.

In witness whereof, I hereunto subscribe my name this 1st day of December, A. D. 1927.
